UNITED STATES PATENT OFFICE.

GEORGE L. GRIMES, OF DETROIT, MICHIGAN.

MOLDING MACHINE.

Application filed December 27, 1920. Serial No. 433,419.

To all whom it may concern:

Be it known that I, GEORGE L. GRIMES, a citizen of the United States, residing at Detroit, county of Wayne, State of Michigan, have invented a certain new and useful Improvement in Molding Machines; and declare the following to be a full, clear, and exact description of the same, such as will enable others skilled in the art to 10 which it pertains to make and use the same, reference being had to the accompanying drawings, which form a part of this specification.

My invention relates to molding machines 15 for use in various founders' molding operations for producing castings.

The principal object of this invention is 20 an improvement in the general construction and operation of machines of this character.

25 A further object is to provide means for effecting a preliminary jolting of the flask to compact the sand about the pattern, and also to hold the sand while the flask is turned to an inverted position.

30 A further object is to provide an improved mounting of the swinging or pressure arms against which the flask is forced and which also serves to support the flask while the pattern is removed therefrom,— 35 the construction being such that the arms may be swung either into an operative position over the flask, or laterally therefrom as required.

40 A further object is to provide means whereby the arms may be swung in one direction only in order that they may not interfere with the oscillation of the frame when the flask is removed.

45 A further object of the invention is to provide means for adjusting the member to which the swinging arms are pivoted nearer to or farther from the flask supporting platform, to adapt the machine for the reception of flasks of relatively different heights.

50 A further object of the invention is to provide an improved bearing for the trunnion of the rotatable frame carrying the flask platform and the swinging or pressure arms, whereby it may be oscillated with a minimum expenditure of power or effort and without lateral play.

55 A further object of the invention is to provide means whereby the flask carrying platform may be operated to jolt the sand around the pattern to be followed by an upward movement of the flask carrying plat-

form toward the pressure arms to clamp the bottom and follow boards upon the flask, the oscillating frame being then reversed that the pattern may be removed from the 60 flask by an upward (opposite) movement of the flask carrying platform, to which the follow or pattern board is attached.

With the foregoing and other objects in view which will appear as the description 65 proceeds the invention further resides in the combination and arrangement of parts and in the details of construction herein-after described and claimed, it being understood that changes may be made in the 70 precise embodiment of the invention herein disclosed without departing from the spirit of the same.

In the accompanying drawings forming 75 part of this specification:

Figure 1 is a side elevation of the machine, with parts broken away, showing in dotted lines the platform raised toward the pressure arms, as when clamping the bottom and follow or pattern-boards upon the flask 80 preparatory to reversing the latter.

Figure 2 is a side elevation of the machine with the platform in an inverted position, showing the flask in dotted lines resting upon the pressure arms, with the follow-board and pattern attached to the platform but withdrawn from the flask. 85

Figure 3 is a vertical longitudinal sectional view of the machine with the flask supporting platform in its lowermost position, as in Figure 1. 90

Figure 4 is a plan view of the machine showing the pressure-arms in dotted lines, as they would appear when swung toward one side of the machine. 95

Figure 5 is a front elevation of the machine, with parts broken away and in section to more clearly disclose the construction of certain parts, showing also the means whereby the pressure-arms may be adjusted 100 nearer to or farther from the flask supporting platform as may be required to accommodate the different sizes of flasks carried by the latter.

Figure 6 is a side elevation of an automatically operated valve for the delivery of air to and from the cylinder below the piston, to provide for both the jolting and lifting of the flask supporting platform. 105

Figure 7 is a cross sectional view through 110 the automatic valve, taken on or about line 7—7 of Fig. 8.

Figure 8 is a cross sectional view of the valve taken at right angles to the preceding view and on or about line 8-8 of Figure 7.

5 Figure 9 is an inverted plan view of the valve.

Referring now to the letters of reference placed upon the drawings:

A, denotes a main frame or base having 10 a standard A' to which is bolted a bearing A², to receive the trunnion B of an oscillating frame B'

Fitted in the respective ends of the bearing A² to receive the trunnion B, are wedge 15 shaped collars b, b, and rolls b' b'. Between the end of the journal bearing and the nut B^a, and screwed to the end of the trunnion, is a ball-bearing b², to relieve the friction caused by the thrust of the oscillating 20 frame against the end of the bearing.

C, is a flask supporting platform from which rises a U or yoke-shaped frame C' to which are bolted beveled cleats C², overlapping the beveled edges B³, of the oscillating frame B'.

D, is a cylinder supported in the frame B' that it may oscillate therewith. D' is a piston fitted to the cylinder D. D², is a piston 30 rod bolted at its outer end to the U or yoke-shaped frame C' that the latter may be forced across the face of the oscillating frame B' by the operation of the piston.

E, E, are a pair of swinging pressure arms 35 respectively pivoted to a plate F, bolted at f, (see Figure 5) to the oscillating frame B'. E' is a shoulder on the pivot end of the arms adapted to abut against the frame, to insure the arms swinging only in one direction when not in position over the flask.

40 The back of the plate F is provided with a plurality of ribs F^a, adapted to enter a series of corresponding parallel recesses b³ in the face of the oscillating frame B', (see Figure 3) to provide for the adjustment of 45 the pressure arms with reference to the flask supporting platform C, whereby the machine may be adapted to receive flasks of varying heights.

E², denotes a plurality of adjustable 50 hand-screws designed to bear against the board G which carries a flask G'. G², is the usual follow or pattern board bolted to the platform C, to which is secured a pattern G³.

H, denotes an air inlet pipe leading from 55 an air compressor (not shown) to a valve H^a. H' indicates a valve for manually controlling the delivery of air to the cylinder D, that the flask may be either jolted to pack the sand around the pattern or lifted preparatory to turning over the flask to withdraw the pattern as may be required.

H² is a pipe leading from the valve chamber H' through the trunnion B to an automatically controlled valve in the valve 60 chamber I bolted to the oscillating frame B',

a flexible connection H³ being provided between the sections of the pipe H², leading through the trunnion and that connected with the valve chamber to permit the pipe flexing when the frame B' is oscillated.

70 I' is a pipe also leading from the valve chamber H' through the trunnion B to the cylinder D, the latter pipe being also fitted with a flexible pipe or joint I².

h indicates a manually operated lever for 75 rotating the valve H', whereby communication may be established between the inlet pipe H and the pipe H²,— or between the inlet pipe H and the pipe I' as required.

J, is a pipe leading from the pipe I' to a 80 relatively small cylinder J' bolted to the main supporting frame. J² is a plunger having a rod J³ adapted to be projected by the pressure of air delivered to the cylinder into the path of a foot treadle K, pivoted to 85 the main supporting frame.

J⁴ is a spring designed to return the plunger J³ to its initial position upon cutting off the supply of air to the cylinder, whereby the treadle K may be again operated. The treadle K is connected by a link K' with a bell-crank lever K² pivoted in a bracket K³ secured to the standard of the main supporting frame.

K⁴ is a locking bolt pivoted to the bell- 90 crank lever, adapted to enter recesses B^b, B^b, in the oscillating frame B' to lock the latter when rocked from one position of its movement to the other position of its movement and until manually released by the depression of the treadle.

L^a denotes a rod extending downwardly 95 from the yoke-shaped frame C' and movable therewith on which is mounted a roller L^b adapted to oscillate a valve rod L^c upon which are mounted opposing cams L^d, L^d, adapted to be acted upon by the roller L^b to alternately reverse the direction of rotation of the valve disc L^e upon the lower end of the rod. The valve disc L^e is provided 105 with a port L designed to alternately open and close the port l (shown in Figure 7 and in dotted lines of Figure 9) in the valve chamber that air admitted to the valve chamber from the pipe H² may pass from said port l around a peripheral groove or channel m in the plunger valve M, and out through a pipe L^f (see Fig. 7) to the cylinder D, to lift the flask supporting platform. 110

115 Upon the roller L^b carried by the rod L^a contacting with the other or opposing cam L^d due to the reverse movement of the rod, air will be admitted through the port l² to the back of the plunger valve M, thereby 120 forcing the plunger valve to the right (see Figure 7) against the action of the spring l³ thus cutting off the admission of air to the valve chamber through the port l and opening the pipe L^f that the air delivered to the 130

cylinder D may be exhausted;—thereby releasing the flask supporting platform and effecting a jolting of the sand around the pattern. The valve disc is also provided with 5 a port L' which when brought into registration with the port L³ permits the air in the valve chamber to exhaust therethrough that the spring l³ may be effective to return the plunger valve M to the position shown 10 in Figure 7.

N, indicates a spring to force the valve L⁶ to its seat. L⁷ is a valve for closing the exhaust pipe L⁶ that the air admitted to the cylinder D may lift the platform C whereby 15 the flask carried by the platform may be forced against the pressure arms E, E¹, thereby clamping the bottom and follow boards upon the flask,—the previous jolting action of the flask carrying platform being 20 suspended for the time by the closure of the valve L⁷.

The valve L⁷ is connected by the pipe L⁶ to the valve casing at the back end of the plunger M so when the valve L⁷ is closed 25 there is an equal pressure at both ends of the plunger M and the spring l³ will return the plunger M to its initial position regardless of the operation of the top cam L⁸.

If desired a handle L^m shown in dotted 30 lines in Figure 5, may be attached to the rod L^a to rotate the roller L^b out of the path of the opposing cams L^d L^d, the plunger valve will then remain in the position shown in Figure 7, the air admitted to the valve 35 chamber from the pipe H² passing around the peripheral channel m in the valve plunger M and through the pipe L⁵ to the cylinder forcing the platform C with the flask thereon toward the pressure arms as before 40 explained.

If this course is followed it will not be necessary to close the valve L⁷ to effect the upward movement of the flask carrying platform.

45 Having indicated the several parts by reference letters the construction and further operation of the device will now be readily understood.

The machine having been brought to the 50 position indicated in Figures 1 and 3 the follow board G² with the pattern secured thereto is mounted on the platform C with a flask G' properly adjusted and held against displacement in the usual manner. 55 Sand is then placed within the flask and air under pressure admitted to the cylinder below the piston D' by the adjustment of the valves H and H' as previously indicated;—the air passing from the valve H' through 60 the pipes leading from the valve chamber to the automatically controlled valve in the chamber I, whereupon the piston is forced upwardly carrying with it the platform C on which the flask is mounted. The upward 65 thrust of the piston rod having raised the

yoke-shaped frame C' the roller L^b on the depending rod L^a carried by the yoke-shaped frame will by contact with the cams on the rod L^c oscillate the latter and thereby operate the automatic valve as has been heretofore described. Through the operation of the automatic valve the air in the piston is exhausted permitting the platform C with its flask to drop by gravity causing the sand to pack around the pattern. This operation is repeated again and again until the mold is formed. When the mold is completely formed the board G is placed upon the flask, the swinging arms E, E¹, are then adjusted in position over the flask and air 70 admitted again to the cylinder to force the platform upwardly carrying with it the flask as before. The valve L⁷ is then closed that the flask may be brought into contact with the pressure arms E, E¹, to clamp the 75 bottom and follow boards upon the flask, whereupon the hand-screws E³ are adjusted to insure perfect contact between the board and the mold at all points,—it being obvious that air delivered to the cylinder will 80 force upwardly the platform C with its flask thereby compressing the sand in the latter. 85

The board G covering the flask being now held in position by the pressure of air in the cylinder the platform with the flask may 90 be reversed as shown in Figure 2 through the operation of a suitable roll-over mechanism (not shown) described in a co-pending application filed by me December 27, 1920, Serial No. 433,420—and upon the admission 95 of air into the cylinder through the pipe I', the piston D' will be forced upwardly thereby lifting the platform and pattern attached thereto from the flask—as indicated in dotted lines. 100

105 The flask is then removed from the pressure arms that the oscillating frame may be returned to its initial position to receive a new flask.

Having thus described my invention what I claim is:

1. In a molding machine, an oscillating frame, a cylinder supported by the frame, a yoke-shaped frame slidable on said frame and adapted to oscillate therewith, a flask or mold carrying platform forming a unitary part of the yoke-shaped frame; a piston, slidable in the cylinder, and connected with the yoke-shaped frame, laterally swinging arms adapted to bear upon the cover of the flask or mold and adjustably mounted upon the oscillating frame, and means for admitting air under pressure to the cylinder to actuate the flask or mold carrying platform, whereby the cover plate may be 115 clamped in position or the pattern withdrawn from the flask. 120

2. In a molding machine, an oscillating frame having beveled side walls, a cylinder supported by the frame, beveled cleats bolted 130

to the yoke-shaped frame and overlapping the beveled side walls of the oscillating frame, whereby the yoke-shaped frame may slide upon the first named frame and oscillate therewith, a mold or flask supporting platform forming a unitary part of the yoke-shaped frame, a piston slidable in the cylinder and connected with the yoke-shaped frame, a member adjustably secured to the oscillating frame, a pair of laterally swinging arms pivoted to said member adapted to bear upon the cover of the flask or mold, and means for admitting air under pressure to the cylinder to actuate the flask or mold carrying platform.

3. In a molding machine, an oscillating frame, a yoke-shaped frame slidably connected with the oscillating frame having a flask or mold supporting platform forming a unitary part thereof, a pair of laterally swinging arms adapted to bear upon the cover of the flask or mold, and adjustably mounted upon the oscillating frame with reference to the plane of the mold, a cylinder supported by the oscillating frame beneath the yoke of the mold supporting platform having a slideable piston connected with the yoke, and means for admitting air to said cylinder under pressure.

30 4. In a molding machine, an oscillating frame, a yoke-shaped frame slidably connected with the oscillating frame that it may swing therewith, a mold supporting platform forming a unitary part of the yoke-shaped frame, an adjustable member bolted to the oscillating frame having a plurality of parallel ribs adapted to enter corresponding recesses in said oscillating frame, a pair of laterally swinging arms pivoted to the adjustable member, a cylinder supported by the oscillating frame beneath the yoke of the mold supporting platform having a slideable piston connected with the yoke, and means for admitting air into said cylinder under pressure to actuate the platform.

45 5. In a molding machine, an oscillating frame, a mold supporting platform slidably connected with the oscillating frame, a pair of laterally swinging arms pivotally connected with the oscillating frame, means for limiting the lateral movement of said swinging arms toward one side of the machine, and means for actuating the mold supporting platform, whereby the cover plate of the flask may be clamped in position and the pattern withdrawn from the flask.

60 6. In a molding machine, an oscillating frame having a trunnion, a pair of co-acting wedge shaped collars fitted to one end of the trunnion, a roller bearing fitted to the other end of the trunnion, a journal bolted to the main frame of the machine adapted to receive the trunnion, wedge shaped collars and roller bearing, a nut screwed to the 65 end trunnion, a ball-thrust bearing between

the nut and the journal, a frame fitted with a mold supporting platform and slidably connected with the oscillating frame, a pair of pressure arms pivoted to the oscillating frame, and means for actuating the mold supporting platform toward the swinging arms, whereby the swinging arms may clamp the cover plate upon the molds.

7. In a molding machine, an oscillating frame mounted upon a trunnion bearing, pressure arms pivoted to the frame, a frame provided with a flask supporting platform slidably mounted upon the oscillating frame, a cylinder carried by the oscillating frame; a piston, slideable in the cylinder, and connected with the frame of the flask supporting platform, a valve for manually controlling air under pressure, an automatically operated valve adapted to receive air under pressure from said manually operated valve for delivery to the cylinder, whereby a preliminary jolting of the flask supporting platform may be effected, said automatically operated valve being actuated through the movement of the frame of the flask supporting platform.

8. In a molding machine, an oscillating frame mounted upon a trunnion bearing, pressure arms pivoted to the frame, a frame provided with a flask supporting platform slidably mounted upon the oscillating frame, a cylinder carried by the oscillating frame, a piston connected with the frame of the flask supporting platform and slideable in the cylinder, a valve for manually controlling air under pressure, an automatically operated valve adapted to receive air under pressure from said manually operated valve for delivery to the cylinder, said automatic valve comprising an air delivery port leading to the cylinder, a slideable plunger valve adapted to control the passage of air from the air inlet port in the valve chamber to the discharge port leading to the cylinder and the exhaust from the latter, an oscillating disc-valve for controlling the delivery of air from the inlet port to actuate the plunger valve, whereby the air may pass to its cylinder, a stem extending through the valve chamber, upon which the disc-valve is mounted, fitted with a pair of opposing cams spaced apart, a member carried by the frame of the flask supporting platform adapted to alternately act upon said cams to actuate the disc-valve alternately in opposite directions whereby the air may be delivered to the cylinder to effect a preliminary jolting of the flask supporting platform, to clamp the boards upon the flask.

In testimony whereof, I sign this specification in the presence of two witnesses.
GEORGE L. GRIMES.
